DOOR CHECK

Frank Kukula, Chicago, Ill.

Application June 6, 1938, Serial No. 211,999

4 Claims. (Cl. 292—263)

The present invention relates to door checks and has for its principal object the provision of a door check whereby the door may be maintained in an open rigid position so that the same may not be closed either by wind or by any other agency.

A still further object of the present invention is the provision of a door check most suitable for employment in connection with garage doors.

A still further object of the present invention is the provision of a door check consisting of a pair of pivoted arms, one of the arms engaging the door frame while the other engages the door, and so arranged that said arms may angularly shift when the door is closed and extend when the door

is opened, with means upon the door to engage one of said arms when the door remains in an open position, to maintain said arms in a rigid immovable position.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views;

30 Fig. 1 is a top plan view showing the door in an open position with the door check in an extended operative position;

Fig. 2 is a similar view with door closed showing the door check in a folded inoperative position;

35 Fig. 3 is a perspective view of the door showing the same in an open position with the door check in an extended operative position; and

Fig. 4 is a perspective view of a plate attachable to the door and which is adapted to engage the 40 door check to maintain the same in an operative position when the door is open.

Referring to the present drawing there is shown therein a door frame including a vertical side bar 10 upon which door 11 is suspended by means 45 of hinges 12. The horizontal upper frame bar is indicated by 13.

Affixed to the under face of the horizontal upper frame bar 13 by means of a plurality of screws 14 is an oblong plate 15 having a free end 50 projecting inwardly into a dwelling or garage and beyond the door frame. Pivotedly affixed as at 16 to the free end of said oblong plate 15 is arm 17. The opposite end of said arm 17 pivotally connects with arm 18 as at 19. Integrally formed 55 at the opposite end of said arm 18 and down-

wardly projecting therefrom substantially at a right angle is bar 20 terminating in a handle 21 at its lower end. Said bar 20 passes through a pair of brackets 22 positioned adjacent the free edge and on the inner face of door 11, to maintain said bar 20 in proximity to the said free edge of door 11 and in parallel relation therewith, as is clearly seen in Fig. 3.

Handle 21 remains on a plane co-extensive with arm 18 and is in parallel relation therewith, so that when the door remains in an open position shown in Fig. 1 both said arm 18 as well as said handle 21 remain in an angular relation with the door.

The invention further includes a supporting 15 plate 23 having an integral leg portion 24 by means of which said plate 23 may be mounted upon the inner face of the door by means of screws passing through screw holes 25 in said leg portion 24 of plate 23. Said plate 23 remains 20 at an obtuse angle with relation to leg portion 24 and further is of arcuate formation on a horizontal plane, for the purpose hereinafter stated. Plate 23 has adjacent its upper edge a notch 26 struck out with a resulting lug 27 projecting upwardly and above the upper edge of said plate 23 25 as is clearly seen in Fig. 4.

From the hereinabove description it will be seen that brackets 22 permit rotary as well as upright shifting movement of bar 20. Thus said 30 bar 20 and bracket 22 constitute pivotal means for the adjacent end of arm 18.

When door 11 remains in a closed position, arms 17 and 18 remain in an angular relation seen in Fig. 2, the same remaining disposed immediately 35 below the lower face of the upper horizontal frame bar 13. In that position arm 18 rests upon the upper edge of plate 23. When the door is shifted into an open position, arms 17 and 18 shift until the same assume an extended position 40 illustrated in Figs. 1 and 3. During the process of the opening of the door arm 18 shifts upon the upper edge of plate 23 until the door is completely opened at which time said arm 18 will automatically fall within notch 26 of said plate 45 23, lug 27 constituting a guide preventing displacement of said arm 18.

In order to close the door, bar 20 is manually shifted in an upward direction for elevating arm 18 from notch 26 for the purpose of bringing 50 said arm above the continuation line of the upper edge of plate 23, and while maintaining said arm 18 in that position, manual pressure is applied at handle 21 toward door 11 for the purpose of shifting arm 18 upon the upper edge of 55

plate 23 and for facilitating the respective angular shifting movement of arms 17 and 18. On giving a push to door 11 for the purpose of closing the same, arms 17 and 18 will gradually angularly shift, arm 18 riding upon the upper edge of plate 23 toward the inner face of door 11. When the door is completely closed arms 17 and 18 will assume the position illustrated in Fig. 2.

When door 11 is completely opened arm 18 automatically drops into notch 26 due to gravity as well as due to the drag exerted thereupon by bar 20.

Due to the fact that said plate 23 remains at an obtuse angle with relation to leg portion 24 and further due to the fact that said plate 23 is of slight arcuate formation, the portion thereof adjacent its free end, will substantially remain in perpendicular relation with the longitudinal axis of arms 17 and 18 when said arms are in extended position, as is clearly seen in Fig. 1. This arrangement will not only facilitate said arm 18 for automatically dropping within notch 26 when said arms 17 and 18 are fully extended at the time the door is fully opened, but will at the same time tend to rigidly hold arm 18 against lateral movement.

While there is described herein a preferred embodiment of the present invention, it is nevertheless to be understood that minor changes may be made therein without departing from the spirit and scope of the invention as claimed.

What I claim as new is:

1. A door check comprising a pair of arms pivotally joined together by one of their ends, one of said arms being pivoted to the door frame, a bar integrally formed with the other of said arms and in an angular relation therewith, said bar being pivotally supported upon the door and being adapted for longitudinal shifting movement thereupon, and a plate mounted upon the door and in a transverse relation with said last named arm for supporting the same as the same makes shifting movement to a folded or unfolded position, said plate being provided with a notch at a point of said plate which coincides with said last named arm when the latter remains in an unfolded position for permitting said last named arm to fall therewithin due to gravity of said arm and to the drag exerted thereupon by said bar for the purpose of engaging said arm with said plate for maintaining said arm in a stationary position when the door remains opened.

2. A door check comprising a pair of arms pivotally joined together by one of their ends, one of said arms being pivoted to the door frame, a bar integrally formed with the other of said arms and in an angular relation therewith, said bar being pivotally supported upon the door and being adapted for longitudinal shifting movement thereupon, and a plate mounted upon the door and in a transverse relation with said last named arm for supporting the same as the same makes shifting movement to a folded or unfolded position, said plate being provided with a notch at a point of said plate which coincides with said last named arm when the latter remains in an unfolded position for permitting said last named arm to fall therewithin due to gravity of said arm and to the drag exerted thereupon by said bar for the purpose of engaging said arm with said plate for maintain-

ing said arm in a stationary position when the door remains opened, said bar being adapted for manual longitudinal shifting movement for elevating said arm and bringing the same out of the said notch preparatory to swinging the door into a closed position for the purpose of permitting shifting of said arms into an angular folded position.

3. A door check comprising a pair of arms pivotally joined together by one of their ends, one of said arms being pivoted to the door frame, a bar integrally formed with the other of said arms and in an angular relation therewith, said bar being pivotally supported upon the door and being adapted for longitudinal shifting movement thereupon, and a plate mounted upon the door and in a transverse relation with said last named arm for supporting the same as the same makes shifting movement to a folded or unfolded position, said plate being provided with a notch at a point of said plate which coincides with said last named arm when the latter remains in an unfolded position for permitting said last named arm to fall therewithin due to gravity of said arm and to the drag exerted thereupon by said bar for the purpose of engaging said arm with said plate for maintaining said arm in a stationary position when the door remains opened, said bar being adapted for manual longitudinal shifting movement for elevating said arm and bringing the same out of the said notch preparatory to swinging the door into a closed position for the purpose of permitting shifting of said arms into an angular folded position.

4. A door check comprising a pair of arms pivotally joined together by one of their ends, one of said arms being pivoted to the door frame, a bar integrally formed with the other of said arms and in an angular relation therewith, a plurality of brackets mounted upon the door for guiding said bar in its rotary and longitudinal shifting movements, said bar and said brackets constituting a means for pivotal mounting upon the door of one end of said last named arm, and a plate mounted upon the door below said last named arm and in transverse relation therewith, said plate having a notch provided at the adjacent outer free end of said plate, said arms being adapted to assume folded, angular relative position when the door remains closed or partially opened, said last named arm being adapted to be supported upon said plate when the door is in a closed or partially opened position, said last named arm being adapted to automatically fall within said notch when the door is completely opened for the purpose of maintaining said last named arm against lateral shifting movement and for tending to maintain both of said arms in a relative rigid extended position for rigidly maintaining the door in an open position, said bar being adapted for upright shifting and rotary movements for elevating said last named arm and for imparting thereto an initial shifting movement for conditioning the door for an unobstructed swinging thereof into a closed position.

FRANK KUKULA. 70
